UNITED STATES PATENT OFFICE.

JAMES M. IDE, OF TROY, NEW YORK, ASSIGNOR TO GEORGE P. IDE & CO.,
OF TROY, NEW YORK, A FIRM.

SHIRT-WAIST.

SPECIFICATION forming part of Letters Patent No. 731,369, dated June 16, 1903.

Application filed December 14, 1900. Serial No. 39,840. (No model.)

To all whom it may concern:

Be it known that I, JAMES M. IDE, a citizen of the United States, residing at Troy, county of Rensselaer, and State of New York, have

5 invented certain new and useful Improvements in Shirt-Waists, of which the following is a specification.

The invention relates to such improvements; and it consists of the novel construction and combination of parts hereinafter described and subsequently claimed.

Reference may be had to the accompanying drawings, and the reference characters marked thereon, which form a part of this 15 specification.

Similar characters refer to similar parts in the several figures.

Figure 1 of the drawings is a view in front elevation of a shirt-waist embodying my invention, a portion of the front of the garment being broken away to better illustrate the invention. Fig. 2 is a vertical section of the same, taken on the broken line 2 2 in Fig. 1. Fig. 3 is a similar view of a modified form of 25 construction for reinforcing the garment at the waist-line.

My invention relates to that class of outer garments known as "shirt-waists," particularly those adapted for men's wear, wherein 30 it is desirable to maintain the lower end of the waist-body and the upper end of the trousers in such relative positions that one shall overlap the other without separation at any point.

35 The object of my invention is to provide a shirt-waist having means for detachably securing thereto suspenders such as are commonly used with trousers and separate and independent means for detachably securing 40 thereto trousers provided with the ordinary suspender-buttons.

In carrying out my invention I provide the shirt-waist at or near its waist-line with means for detachably connecting thereto either on 45 the inner side or outer side the trousers and separate means for detachably connecting thereto ordinary suspenders.

Referring to the drawings, 1 represents the body of the shirt-waist, having the usual neck- 50 opening 2 and sleeves 3.

The garment is preferably reinforced at or near its waist-line, as by stitching thereto a reinforcing-strip 4 a short distance above its lower end 5, as shown in Figs. 1 and 2.

The garment is provided at or near its 55 waist-line along said reinforced portion with a series of buttonholes 6, severally adapted to be detachably connected with the usual buttons 7 on the upper end of the trousers, as indicated by dotted lines in Fig. 2, where- 60 in the upper end of the trousers 8 is indicated by dotted lines. The garment is also pro- 65 vided with a series of tabs 9, severally se- cured at one end to the body of the garment near its waist-line, preferably to said rein- 70 forced portion, and severally provided with buttons 10 or other means for detachably connecting the free ends of said tabs with the ends 11 of the suspenders 12, adapted to pass over the shoulders of the wearer. The shoul- 75 der portions of the suspenders may pass loosely through supporting-loops 13. (Indi- cated by dotted lines in Fig. 1.) The length of the suspenders is so limited as to leave the waist with a full body above the waist-line 75 when the opposite ends of the suspenders are connected at front and back with the respec- tive tabs 9.

It may be seen from an inspection of Fig. 2 that when the several parts are connected 80 as above described the upper end of the trousers will be connected with the shirt- 85 waist at its waist-line in such a manner that the upper edge of the trousers is wholly con- cealed by the lower end of the waist, while at the same time the weight of the trousers is supported by the suspenders through the intervening tabs and reinforced portion of the waist-body, leaving the waist-body above the waist-line free and unconfined. I am 90 thus able to give any desired degree of full- 95 ness to the body of the garment without inter- fering with the proper support of the trou- sers.

It will be seen that it is not necessary to de- 95 tach the suspender-ends to remove the waist from the trousers, the separation being ac- complished merely by unbuttoning the but- tonholed portion of the waist from the trou- sers-buttons, the suspenders being left con- 100

nected with the respective tabs and being removed from and applied to the person of the wearer while connected with the waist.

The tabs 9 are preferably secured to the reinforced portion of the garment adjacent to the respective buttonholes 6, so that the weight of the trousers is supported by the suspenders without being transmitted through any unreinforced portion of the garment.

10. By employing a reinforcing-strip 4 I am able to leave the lower end 5 of the waist loose and unconfined in use. If desired, however, the waist can be reinforced by folding the lower end of the body upon itself, as 15 shown at 14 in Fig. 3, the buttonholes 6 being formed in such folded portion.

The tabs 9 are preferably secured at their lower ends to the body of the garment by stitching, their upper ends being free, thus 20 facilitating the connection and disconnection of the suspender-ends therewith.

I am thus able to provide a complete shirt-waist to which any of the usual forms of trousers-suspenders may be detachably applied 25 as easily as they are applied to trousers for the purpose of supporting the same in differing adjusted positions and to which trousers having the usual suspender-buttons either on the inner or outer side of the waistband 30 may be secured independently of the suspenders. When the buttons are on the outer side of the trousers, the waist overlaps the trousers, and when the buttons are on the inner side the waist is tucked in and the trousers 35 overlap the waist.

What I claim as new, and desire to secure by Letters Patent, is—

1. A shirt-waist having at or near its waist-

line separate means for detachably connecting thereto both the trousers and the suspenders, substantially as described. 40

2. A shirt-waist having at or near its waist-line a series of buttonholes adapted to connect respectively with the trousers-buttons, and a series of tabs severally secured at one 45 end to the body of the garment adjacent to the respective buttonholes, and provided with means for detachably connecting therewith the opposite ends of suspenders adapted to pass over the shoulders of the wearer, substantially as described. 50

3. A shirt-waist having at or near its waist-line a series of buttonholes adapted to register with trousers-buttons, and a similar series of suspender-fastenings for supporting 55 the waist-line of the waist independently of such buttonholes substantially as described.

4. A shirt-waist having at or near its waist-line a series of buttonholes adapted to register with trousers-buttons, a reinforcing-strip 60 for each buttonhole, through which the buttonhole is made, projected above the button-hole and provided on the projection with a suspender-fastening, substantially as described.

5. A shirt-waist having buttonholes for detachably connecting thereto the buttons of the waistband of trousers, and having buttons for detachably connecting thereto the buttonholes of the opposite ends of trousers-suspenders. 65

In testimony whereof I have hereunto set my hand this 8th day of December, 1900.
